SYSTEM FOR SETTING OFF EXPLOSIVE CHARGES

Maurice P. Lebourg, Houston, Tex., assignor, by mesne assignments, to Borg-Warner Corporation, Chicago, Ill., a corporation of Illinois

Application November 29, 1951, Serial No. 258,949

2 Claims. (Cl. 102—20)

This invention relates to systems for setting off explosive charges and more particularly to systems whereby a plurality of explosive charges may be set off in succession.

Explosive charges such, for example, as a string of shaped explosive charge units adapted to be detonated in succession in a borehole, are conventionally detonated by means of a primacord fuse which is threaded through each unit in series so that as the detonation wave travels along its length to a point within each unit, the explosive charge therein will be detonated. The primacord fuse is brought into the units by means of through-bores disposed near the rearward ends of the explosive charges and having cylindrical walls to prevent the escape of explosive material therefrom. In order to insure effective detonation of the explosive charges by the detonation wave from the primacord fuse, these cylindrical walls must be made very thin. A shaped explosive charge assembly embodying this construction is shown in Figure 9B of the pending U. S. application Serial No. 123,003.

The construction described briefly above has been found effective where the entire string of explosive charge units is shielded or encased in a pressure-resistant housing to keep out the borehole liquid. In perforating oil wells, however, it is often desirable and sometimes necessary that the apparatus be expendable and so constituted that the energy developed upon detonation of the charges breaks it into small pieces which may be allowed to drop harmlessly to the bottom of the well. In apparatus of this type, the shaped charge containers and the primacord fuse are all exposed to the pressure in the borehole which may be very high at the depths at which well perforating operations are conducted. It has been found that this pressure may be sufficiently high to break down the thin cylindrical walls which define the through-bores for receiving the primacord fuse, thereby permitting borehole liquids to enter the shaped charge container with the result that the action of the shaped charge is seriously if not wholly impaired.

One method of preventing the admission of borehole liquids into the individual shaped charge containers is to strengthen the thin cylindrical walls. However, the strengthening of these walls shields the explosive charge from the detonation wave of the primacord fuse and tends to prevent effective detonation of the explosive charge.

It is, therefore, an object of this invention to provide an improved system for firing a plurality of explosive charges in succession.

It is another object of the invention to provide means for setting off a series of explosive charges which are housed in individual containers adapted to withstand high external pressures.

It is another object of the invention to provide a system for setting off a series of explosive charges successively without the use of physical connecting means between the charges prior to detonation.

It is another object of the invention to provide means

2

for setting off an explosive charge without the use of a primacord fuse.

The above and other features and objects of the invention may be attained by providing an explosive charge unit comprising a container having walls sealing it against external media under pressure. Within each container there is provided a first chamber for receiving a main explosive charge, a second chamber communicating with the first chamber for receiving means such as a booster charge for setting off the main explosive charge, and a third chamber communicating with the other chambers for receiving an auxiliary shaped explosive charge adapted to be set off with the main explosive charge.

A series or string of these units may be stacked in a supporting frame with the auxiliary shaped charge in the first unit arranged to direct the explosive jet, which will emanate therefrom upon detonation, toward the chamber containing the means for setting off the main explosive charge in the next unit. Thus, when the auxiliary shaped charge of the first unit is set off, an explosive jet will be produced which will penetrate the container of the second unit to set off the explosive charges therein. With each successive unit arranged to be set off by the explosive jet from the auxiliary shaped charge of the preceding unit, all of the units will be set off in rapid succession without the use of physical connections between the units prior to detonation.

It will be understood that the explosive jet from each of the auxiliary shaped explosive charges is sufficiently potent to penetrate the strong container wall which seals the means for setting off the explosive charges in the next or adjacent unit. Also, the nature of the explosive jet formed by shaped explosive charges is such that wall means of considerable strength may be used to seal the charges themselves against the admission of external media under pressure without destroying the effectiveness of the jet. As a result the external container walls of each unit may be made strong throughout.

In order to set off the explosive charges of the first unit of the series, a pressure resistant container may be mounted in the supporting frame adjacent the first unit. This container may be provided with a starting shaped explosive charge having its jet axis directed toward the means for setting off the first unit. Detonation of the starting shaped explosive charge may be effected by any suitable means such as a short primacord fuse attached to a blasting cap which is in turn adapted to be set off by any suitable means such as an electric current derived through electrical conducting means running to a remote point, such as the surface of the earth, for example.

The invention may be better understood from the description of a preferred form thereof by the following specification which is taken in conjunction with the drawing.

The drawing comprises a single figure which is a fragmentary view in longitudinal section of a portion of a frame carrying a string of explosive charge units constructed and arranged in accordance with the invention. For purposes of illustration the sectional views of the respective explosive charge units have been developed so that where possible the component parts of each of the units appear in full lateral projection.

Referring to the drawing, the invention is shown as embodied in an explosive charge assembly including a frame 1 (partially illustrated) arranged to support a string of explosive charge units 2—1, 2—2, 2—3, etc. The units are disposed with their respective longitudinal axes in parallel planes spaced apart along the length of the frame and transverse with respect thereto, and each successive unit is angularly displaced in its plane ninety degrees from the preceding unit. The frame 1 is open-sided so that each of the several explosive charge units

is almost fully exposed. The illustrated frame is adapted to be lowered by means of a cable (not shown) into a borehole drilled into the earth so that the explosive charge units might be used to perforate the casing in the borehole, for example.

Each of the explosive charge units is substantially the same with minor exceptions as will be pointed out below, and like identifying numerals are applied to like parts of each unit. Each of the units comprises a pressure-resistant container 3, preferably made of a dense material such, for example, as lead, formed on one end with a threaded, recessed cylindrical opening 4 communicating coaxially with a conical chamber 5 which joins at its apex a smaller cylindrical chamber 6. The other end of each of the units is formed with an outwardly diverging tail portion 7 of substantially circular cross section and entered by a flared recess 8 which communicates with a cylindrical chamber 9 which in turn joins the cylindrical chamber 6 at a steep angle. The tail portion 7 is also entered by a cylindrical opening 10, followed by a conical chamber 11, the apex of which is joined to the chamber 6 by means of a chamber 12.

As best seen in the unit 2-1, a main explosive charge 13 is fitted in the chamber 5. The explosive charge 13 is formed with a lined cavity 13' in its forward end and will, upon detonation starting at its rearward end, provide an explosive jet of extremely high penetrating power directed forwardly along the axis of the charge. Received in the chamber 6 is a booster charge 6' for detonating the explosive charge 13.

For convenience of assembly, the shaped explosive charge 13 may be housed in a contoured casing 14 made of a thin plastic, which may be easily inserted in the chamber 5 of the container 3 and followed by a retaining and sealing cover 15 threaded into the opening 4. If necessary, a gasket 15' may be used between the cover 15 and the container 3 to keep borehole liquid from filling the cavity 13'. Alternatively, the explosive charge may be poured directly into the chamber 5.

The cover 15 may be made amply strong to withstand any pressures which might be encountered in a borehole without destroying the effectiveness of the explosive jet, the intensity of which is such that the cover may be readily shattered.

Received within the chamber 9 and in communication with the booster charge in the chamber 6 is a booster charge 16. The booster charge 16 is sealed in by a pressure-resistant barrier or cap 17, and is adapted to be set off through the barrier by means described more fully below. Received within the chamber 11 is an auxiliary shaped explosive charge 18 retained and shielded by a frangible, pressure-resistant cap 18'. A small booster charge 12' is received in the chamber 12 behind the explosive charge 18. The auxiliary explosive charge 18 is similar to the main explosive charge 13 but is of substantially smaller proportions, and its booster charge 12' is disposed in communication with the booster charges 6' and 16 so as to be set off thereby.

Successive explosive charge units 2-1, 2-2 and 2-3 are so constituted and are so mounted in the frame 1 that the jet axis of the auxiliary shaped charge 18 of the uppermost unit 2-1 is in alignment with the axis of the booster charge 16 of the next following unit 2-2, and the auxiliary shaped charge 18 of the unit 2-2 is in alignment with the booster charge 16 of the next unit 2-3. Thus, when the first unit 2-1 is set off, an explosive jet will emanate from its auxiliary shaped charge 18 which will activate the booster charge 16 of the next unit 2-2, and so on.

Mounted at the upper end of the frame 1 is a waterproof, pressure-resistant container 19 having formed at its lower end suitable cavities for receiving a downwardly directed auxiliary shaped charge 20 shielded by a cap 21 and aligned with the booster charge 16 of the uppermost explosive charge unit 2-1. The upper or apex end of the auxiliary shaped charge 20 communicates

with a closed chamber 22 which receives a firing head 23, which may comprise, for example, a simple primacord fuse 24 and an electrically operated blasting cap 25 for igniting the primacord fuse. The firing head 23 may be connected by means of an electrical conduit 26 to the surface of the earth, the conduit 26 preferably being incorporated in the supporting cable (not shown) whereby the frame 1 is lowered into the borehole. It will be understood, however, that any suitable detonating means may be used for setting off the shaped charge 20. Because the shaped charge 20 is, in the illustrated form of the invention, directed vertically downwardly from a point spaced laterally from the center line of the frame, the booster charge 16 of the unit 2-1 is also disposed vertically. In this one respect the first unit 2-1 differs from subsequent units 2-2, 2-3, etc. in which the booster charge 16 forms an angle with the vertical in order to be in alignment with corresponding shaped charges of preceding units.

In operation, the firing head 23 is set off from a remote point, such as the surface of the earth, after the frame has been lowered to a desired depth in the borehole, thereby detonating the auxiliary shaped charge 20. This sets up an explosive jet in the direction of the unit 2-1 which enters the recess 8 in alignment with the booster charge 16, perforates the barrier 17 and sets off the booster charge 16, this in turn setting off the main explosive charge 13 as well as the auxiliary shaped charge 18 of the unit 2-1. The main explosive charge will send a jet radially outwardly into the wall or casing of the borehole and the auxiliary shaped charge will direct a jet downwardly at an angle toward the next succeeding unit 2-2. This jet will enter the recess 8 in alignment with the booster charge 16 to penetrate the barrier 17 and set off the booster charge of the unit 2-2. Thereafter the main explosive charge of the unit 2-2 will be set off, as will the auxiliary shaped charge 18. In this fashion the charge will be set off in rapid succession without the use of an interconnecting primacord fuse. The rapid series of explosions will cause the frame 1 as well as the respective units 2-1, 2-2, 2-3, etc. to be broken into small pieces which drop harmlessly to the bottom of the borehole. The nature of the jets formed by the auxiliary shaped charges is such that successive, sealed units may be set off in the presence of borehole liquids which might envelope the units. Moreover, the respective units 2-1, 2-2, 2-3 etc. are able, by virtue of their novel construction, to withstand the high pressures which are encountered in a borehole.

While the invention has been described with reference to the drawing showing one preferred form thereof, it will be understood that numerous modifications may be made in the design without departing from the scope of the invention. Thus, for example, the firing head 23 at the upper end of the frame which is adapted to initiate the chain or sequential detonating action may be modified to utilize any suitable detonating means and if preferred the firing head might be incorporated within the first unit 2-1. Also, within the respective explosive charge units other suitable means, such as a small primacord fuse 50 may be used to interconnect the main and auxiliary explosive charges and the booster charge, if such is used. Further, the arrangement for aligning and orienting the respective chambers and cavities in the units may be modified to suit the particular geometrical requirements of the apparatus. Thus other forms and embodiments of the invention coming within the proper scope of the appended claims will readily suggest themselves to those skilled in the art.

What is claimed is:

1. A system whereby a series of exposed explosive charge units may be set off in succession comprising two or more explosive charge units; each unit including a sealed, pressure-resistant container, a main shaped explosive charge, an auxiliary shaped explosive charge and detonating means for the charges housed within the con-

tainer; said shaped charges each having a hollowed out portion sealed by a frangible, pressure-resistant cover; the main and auxiliary charges being arranged within the container to direct the explosive jets, which result therefrom, in different directions; said detonating means being constructed and arranged to be activated by an explosive jet emanating from a point spaced from the unit; an externally exposed pressure-resistant barrier sealing said detonating means in the container and adapted to be pierced by the explosive jet from said point; support means comprising an open-sided frame for carrying said units in spaced apart relationship with each unit exposed and the auxiliary shaped explosive charge of a first unit aimed to direct its explosive jet toward the detonating means of a second unit; and means for activating the detonating means of the first unit.

2. A system as set forth in claim 1, said means for activating the detonating means of the first unit comprising a sealed housing carried by the support means and spaced from the first unit, an auxiliary shaped explosive

charge mounted in the housing and aimed to direct its explosive jet toward the detonating means of the first unit, and means for setting off the said auxiliary shaped explosive charge in said housing from a remote point.
